(57) **CLAIM**

The ornamental design for an oral care implement, as shown and described.

DESCRIPTION

FIG. 1 is a front right perspective view of an oral care implement, showing our new design;

FIG. 2 is a rear left perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

All broken lines shown in the drawings are for environmental purposes only and form no part of the claimed design.

1 Claim, 5 Drawing Sheets
